DESIGN FOR AN ACCESSORY LAMP FOR A COOK STOVE

Bertrand N. Trombley, Birmingham, Mich., as-
signor to The Murray Corporation of America,
Detroit, Mich., a corporation of Delaware

Application March 28, 1946, Serial No. 128,030

Term of patent 7 years

(Cl. D81—25)

To all whom it may concern:

Be it known, that I, Bertrand N. Trombley, a citizen of the United States of America, residing in Birmingham, in the county of Oakland, State of Michigan, have invented a new, original, and ornamental Design for an Accessory Lamp for Cook Stove, of which the following is a specification, reference being had to the accompanying drawing, forming a part thereof, wherein:

Figure 1 is a view in elevation of an accessory lamp for a cook stove, embodying my new design,

Fig. 2 is a plan view of the lamp illustrated in Fig. 1; and

Fig. 3 is a side view of the lamp illustrated in Fig. 2, as viewed from the right-hand end thereof.

I claim;

The ornamental design for an accessory lamp for a cook stove, substantially as shown.

BERTRAND N. TROMBLEY.
